GRINDING MACHINE

Albert W. Wigglesworth, Chicago, Ill., assignor
to Hill-Clarke Machinery Co., Chicago, Ill., a
corporation of Illinois

Application February 3, 1936, Serial No. 62,080

5 Claims. (Cl. 51—95)

This invention relates to machine tools and particularly to grinding machines comprising a base, a work carriage longitudinally reciprocable on the base, a headstock including a rotatable work-engaging member, a tailstock, the head and tailstock being mounted on the work carriage, a rotatable grinding wheel, and a grinding wheel base movable transversely of the machine base to position the wheel in proper relation to the work.

10 Heretofore the rotation of the work-engaging member of the headstock, the longitudinal reciprocation of the work carriage and the rotation of the grinding wheel have been produced by three separate motors or by means for conveying power 15 from overhead shafts to the several parts of the machine to be actuated.

The main object of my invention is to provide improved and simplified means for actuating the moving parts and to eliminate overhead shafting 20 and to reduce the number of motors heretofore required for operating grinding machines of the character described.

Another object is to produce rotation of the grinding wheel and variable speed reciprocation 25 of the work carriage longitudinally of the base by means of one motor located on the grinding wheel base which is movable transversely of the machine base.

In the construction shown and described herein, 30 the invention is embodied in a grinding machine originally adapted for overhead driving means, but the invention is not limited to this particular embodiment.

In the drawings:

35 Fig. 1 is a front elevation of a grinding machine embodying my invention.

Fig. 2 is a transverse, vertical sectional view taken on the line 2—2 of Fig. 1, on an enlarged scale, showing part of the machine in side elevation.

40 Fig. 3 is a rear elevation of part of the machine.

Fig. 4 is a vertical sectional view taken on the line 4—4 of Fig. 3.

45 Fig. 5 shows in side elevation a modified form of part of the driving means shown in Fig. 2.

Fig. 6 shows a rear elevation of the parts shown in side elevation in Fig. 5.

In that embodiment of my invention shown in the drawings, the grinding machine comprises a 50 base 10, a work carriage 11 longitudinally reciprocable on the base 10, headstock 12 having a rotatable work-engaging member 13, and tailstock 14, said head and tailstocks being adjustably mounted on the work carriage 11 and movable 55 therewith. The member 13 is rotated by gearing

operatively connected with a motor (not shown) located in the housing 15 of the headstock.

The grinding machine also comprises a grinding wheel 16 mounted on a wheel base 17 movable transversely of the base 10, and motor 18 also on the wheel base 17. In this embodiment the transverse movement of the wheel base 17 is produced by actuating a hand wheel 19.

The motor 18 is adjustably secured to the wheel base 17 by bolts 18' and has a motor shaft on the 10 extended end of which is mounted a small pulley 20 and a larger pulley 21, the latter preferably being of the multi-grooved type as shown. A plurality of belts 22 connect the pulley 21 with a similar pulley 23 on the shaft 24 on which the grinding wheel 16 is mounted. In Fig. 1 the shaft 24 is 15 shown mounted in bearings 25. The motor 18 thus drives the wheel 16 through motor shaft, pulley 21, belts 22, pulley 23 and wheel shaft 24.

The means for transmitting power from the motor 18 to the work-carriage driving mechanism is best shown in Figs. 2 and 3. A horizontally disposed shaft 26 is rotatably mounted in bearings 27 on the rear wall of the machine, and on one end of said shaft 26 is fixed a wide plain pulley 28. A 20 grooved pulley 29 is also fixed on the shaft 26 inwardly of said pulley 28. A tightener pulley 30 is loosely mounted on the shaft 31 fixed in the arm 32. The arm 32 is pivotally mounted on the shaft 26 by the sleeve 33. A belt 34 connects the 25 pulleys 28 and 29 and engages the tightener pulley 30.

30 On the end wall of the base 10, adjacent the rear of the machine, is pivotally mounted at 35 an arm 36, and extending horizontally from said arm, at right angles thereto, are pulley shafts 37, 38, on which are loosely mounted wide idler or tightener pulleys 39, 40. The drive shaft 41, 35 rotatably mounted in the forward part of the base 10, is operatively connected to the work carriage 11 through gearing (not shown) for reciprocating the said carriage longitudinally of the base 10. A speed-change pulley 42 fixed on the shaft 41, is connected to the pulley 28 on the shaft 26 by a belt 43 which extends through an opening 44 in the rear wall of the left hand side of the base 10 (as viewed in Fig. 3). The belt 43 is engaged by the idler pulleys 39 and 40 as best shown in Fig. 2. Variations in speed of rotation of the drive shaft 41 are obtained by moving the belt 43 longitudinally of the pulley 28 and stepped or cone pulley 42.

35 In Fig. 2 the wheel base 17 is shown in approximately its rearward position. When the wheel base 17 is moved transversely of the base 50 40

55

10, toward the carriage 11, the relative positions of the pulleys 29 and 30 are altered, as indicated by the dotted lines in Fig. 4.

The motor 18 thus drives the shaft 41 at variable speeds for actuating the work carriage 11, the driving connections comprising the motor shaft, pulley 28, belt 34, pulley 29, shaft 26, pulley 28, belt 43, and speed-change pulley 42 on shaft 41, and at the same time the said motor 10 drives the grinding wheel 16, as heretofore explained.

In Figs. 5 and 6 is shown a modified form of driving means, especially designed for a grinding machine in which the motor 45 is larger than the motor 18 and consequently its pulley 46 (corresponding with pulley 20 of motor 18) is not in alignment with the pulley 47 (corresponding with pulley 29) on shaft 26. It will be understood that said pulleys 28 and 29, in Figs. 1 to 4, inclusive, 20 and said pulleys 46 and 47, in Figs. 5 and 6, are located in positions which are the best available in an existing machine originally designed to be operated by separate sources of power for the grinding wheel 16 and for the shaft 26 (operatively connected with the carriage-reciprocating means).

In the modified form the pulleys 21 and 23 and belt 22 correspond to the same numbered parts previously described for driving the wheel 16. 30 The shaft 26 and the plain wide pulley 28 also correspond to the parts similarly numbered in Figs. 1 to 4.

The pulley 46 is connected by a belt 48 with a grooved pulley 49 fixed to the hollow shaft 50. 35 An arm 51 is pivotally mounted on the shaft 50 and carries at its outer end a tightener pulley 52, which is also engaged by the belt 48. Also keyed to shaft 50 is a pulley 53. The shaft 50 is loosely mounted on the stub shaft 54 fixed to the base 17. The pulley 53 is connected by belt 55 to the pulley 47, keyed to shaft 26. An arm 56 pivotally mounted on shaft 26 carries a tightener pulley 57 engaged by belt 55.

As the wheel base 17 is moved transversely of the machine, the relative positions of the pulleys 53 and 47 and associated tightener pulley 57 are altered, the pulley 57 automatically adjusting itself to tension the belt 55. The tightener pulley 52 keeps proper tension on the belt 48.

50 In this form of construction, the motor 45 drives the grinding wheel 16 (through the motor shaft, pulley 21, belts 22, pulley 23 and wheel shaft 24) and also drives the shaft 41 for actuating the work carriage at varying speeds, the drive being from motor shaft to pulley 46, belt 48, pulley 49, shaft 50, pulley 53, belt 55, pulley 47, shaft 26, pulley 28, belt 43 and change speed pulley 42 on shaft 41.

Transverse movement of the wheel and motor base 17, while the machine is in operation, does not interfere with the driving connections between said motor and carriage actuating shaft 41, because the self-adjusting pulleys 30 (Figs. 2, 3 and 4) and 57 (Figs. 5 and 6) automatically 65 retain driving tension on the belts 34 (Figs. 2, 3 and 4) and 55 (Figs. 5 and 6).

Changes may be made in details of construction without departing from the scope of my invention and I do not intend to be limited to the 70 exact form shown and described, except as set forth in the appended claims.

I claim:—

1. In a grinding machine having a base, a work carriage mounted for longitudinal reciprocation 75 on the base, a wheel base and a rotatable grinding

wheel on said wheel base, the wheel base being movable transversely of the first mentioned base, means for simultaneously rotating the grinding wheel and actuating the work carriage from a single source of power, said means comprising a motor mounted on said wheel base, its motor shaft operatively connected with the grinding wheel, a pulley on the motor shaft, a horizontally disposed shaft mounted on the machine base, a pulley fixed on said shaft, a tightener pulley pivotally mounted on said shaft, a belt connecting said pulleys and engaged by the tightener pulley, a drive shaft mounted in the base and operatively connected with the work carriage, and operative connections between the horizontal shaft and said carriage drive shaft. 10 15

2. In a grinding machine having a base, a work carriage mounted for longitudinal reciprocation on the base, a wheel base and a rotatable grinding wheel on said wheel base, the wheel base being movable transversely of the first mentioned base, means for simultaneously rotating the grinding wheel and actuating the work carriage from a single source of power at variable speeds, said means comprising a motor mounted on said wheel base, its motor shaft operatively connected with the grinding wheel, a pulley on the motor shaft, a horizontally disposed shaft mounted on the machine base, a pulley fixed on said shaft, a tightener pulley pivotally mounted on said shaft, a belt connecting said pulleys and engaged by the tightener pulley, a wide plain pulley fixed on said shaft, a drive shaft mounted in the base and operatively connected with the work carriage, change speed elements on said drive shaft, 30 and a belt connecting said horizontal shaft and carriage drive shaft and movable longitudinally of said plain pulley and said change speed elements. 35

3. In a grinding machine having a base, a work carriage mounted for longitudinal reciprocation on the base, a wheel base and a rotatable grinding wheel on said wheel base, the wheel base being movable transversely of the first mentioned base, means for simultaneously rotating the grinding wheel and actuating the work carriage from a single source of power, said means comprising a motor mounted on said wheel base, its motor shaft operatively connected with the grinding wheel, a pulley on the motor shaft, a stub shaft extending horizontally from the wheel base, a hollow shaft loosely mounted on the stub shaft, a pulley fixed on the hollow shaft, a tightener pulley pivotally mounted on the hollow shaft, a belt connecting the said pulleys on the motor shaft and hollow shaft and engaged by the tightener pulley, a second pulley on the hollow shaft, a horizontally disposed shaft mounted on the machine base, a pulley fixed on said shaft, a tightener pulley pivotally mounted on said shaft, a belt connecting said second pulley on the hollow shaft and the pulley on the horizontal shaft and engaged by the tightener pulley, a drive shaft mounted in the base and operatively connected with the work carriage, and operative connections between the horizontal shaft and said carriage drive shaft. 40 45 50 55 60 65

4. In a grinding machine having a base, a work carriage mounted for longitudinal reciprocation on the base, a wheel base and a rotatable grinding wheel on said wheel base, the wheel base being movable transversely of the first mentioned base, means for simultaneously rotating the grinding wheel and actuating the work carriage from a single source of power, said means 70 75

comprising a motor mounted on said wheel base, its motor shaft operatively connected with the grinding wheel, a pulley on the motor shaft, a horizontally disposed shaft mounted on the machine base, a pulley fixed on said shaft, a belt connecting said pulleys, a tightener pulley mounted on a support and engaging said belt, a drive shaft mounted in the base and operatively connected with the work carriage to move the same longitudinally, and operative connections between the horizontal shaft and said carriage drive shaft, said operative connections comprising a belt connecting said shafts, an arm pivotally mounted on the base and a pair of idler pulleys carried by the arm and bearing on said belt.

5. In a grinding machine having a base, a work carriage mounted for longitudinal reciprocation on the base, a wheel base and a rotatable grinding wheel on said wheel base, the wheel base being movable transversely of the first mentioned base, means for simultaneously rotating the grinding wheel and actuating the work carriage from a single source of power, said means comprising a motor mounted on said wheel base, its

motor shaft operatively connected with the grinding wheel, a pulley on the motor shaft, a stub shaft extending horizontally from the wheel base, a hollow shaft loosely mounted on the stub shaft, a pulley fixed on the hollow shaft, a tightener pulley pivotally mounted on the hollow shaft, a belt connecting the said pulleys on the motor shaft and hollow shaft and engaged by the tightener pulley, a second pulley on the hollow shaft, a horizontally disposed shaft mounted on the machine base, a pulley fixed on said shaft, a belt connecting said second pulley on the hollow shaft and the pulley on the horizontal shaft, a tightener pulley mounted on a support and engaging said belt, a drive shaft mounted in the base and operatively connected with the work carriage to move the same longitudinally, and operative connections between the horizontal shaft and said carriage drive shaft, said operative connections comprising a belt connecting said shafts, an arm pivotally mounted on the base and a pair of idler pulleys carried by the arm and bearing on said belt.

ALBERT W. WIGGLESWORTH. 25
